UNITED STATES PATENT OFFICE.

ROBERT C. MACKLEM, OF CLEVELAND, OHIO.

BABY CHAIR.

Application filed March 20, 1923. Serial No. 626,341.

To all whom it may concern:

Be it known that I, ROBERT C. MACKLEM, a citizen of the United States, residing at Cleveland, in the county of Cuyahoga and State of Ohio, have invented a certain new and useful Improvement in a Baby Chair, of which the following is a full, clear, and exact description, reference being had to the accompanying drawings.

10 This invention relates more particularly to a baby chair which is adapted for use either in single or multiple units. When arranged for individual use, my invention contemplates a foldable chair which when open provides commodious space and when closed occupies about the same space as a suitcase.

20 In addition, my invention is directed toward the provision of a chair having a flexible seat which enables a child to assume an easy posture, and which is readily removable and replaceable.

25 The means for carrying out my invention will be hereinafter described in connection with the accompanying drawings and the essential features will be summarized in the claims.

30 In the drawings, Fig. 1 is a perspective view of a chair embodying my invention when used as a community play chair; Fig. 2 is a bottom view of the chair shown in Fig. 1; Fig. 3 is a fragmentary section taken through one of the compartments; Fig. 4 is a perspective view of a foldable chair having the table partially open and having the sides extended; Fig. 5 is a longitudinal transverse section taken through the chair shown in Fig. 4; Fig. 6 is a view showing the chair on edge indicating the foldable side and end portions; and Fig. 7 is a 40 perspective view of the chair in folded position.

45 Referring to Figs. 1 to 3, wherein my invention is illustrated as a stationary play chair, I have shown a plurality of compartments arranged side by side and on opposite sides of a central play table. Each compartment embodies a seat 10 which is removably secured to the chair, as upon brackets 11 and 12, and which is provided 50 with openings 13 and 14 through which the legs of a child extend. The preferred form of seat attachment is illustrated in Figs. 2 and 3 by rods 15 and 16 which extend through hems in opposite ends of the seat and which engage the brackets as illustrated. With this form of attachment, the weight of

the child tends to hold the rods in contact with the brackets.

55 A chair embodying my invention may be made in either single or multiple units but in Fig. 1, the multiple unit is illustrated as having compartments 20 arranged side by side in one row, and compartments 21 similarly arranged in another row on the opposite side of a central play table 24. The compartments may be separated by partitions 22 and 23 respectively which may comprise transverse braces 32 shown in Fig. 2. These braces preferably extend beneath the central play table and transversely thereof and serve as a reinforcement to the vertical supports.

60 As illustrated, the supports comprise longitudinal and transverse members 30 and 31 respectively, which provide an enclosed base. Projecting above the base, I have shown back rests 26 and 27 and side guards 28 and 29 which project above the play table 70 sufficiently to protect the child.

65 Referring now to Figs. 4 to 7, my invention is illustrated in a collapsible chair which when open provides a satisfactory seat of adjustable height, and when closed provides a compact portable package. This form of my invention embodies a frame having side members 40 and 41 and end members 42 and 43 which are disposed in the shape of a rectangle. On one side of the frame, I provide a pair of transverse members 44 and 45 which are spaced apart sufficiently to provide a seat for the child. The seat 46 is also flexible and is provided with 75 openings 47 for receiving the legs of the child and is moreover arranged to be removably attached to the members 44 and 45 respectively. The preferred form of attaching the seat is substantially the same as heretofore described.

80 Positioned across the opening intermediate the members 44 and 45, I provide a closure 50 which may be hinged to the member 44 adjacent the opening and may be provided with a flange 51 extending around the marginal edges thereof so as to provide a play table when open. On the opposite sides of the opening, I prefer to employ a back-rest 52 which is shown as hinged to the member 45. The back rest is preferably arranged to be lowered and locked against the member 45 so as to provide a smooth uninterrupted surface when the chair is folded. To accomplish this, I have shown a pair of 85 90 95 100 105 110

members 53 which serve to connect the table and back rest so that the movement of the table, consequent upon opening or closing thereof, effects a corresponding movement 5 of the back-rest. As illustrated, the members 53 are hinged at 54 to the back-rest and at 55 to the table. The attachment with the table embodies a lost motion connection to permit movement of the table through 180 degrees while the back rest is permitted to move only a fractional part thereof.

To close the side of the frame opposite the table, I have shown a pair of closure members 60 and 61 which extend longitudinally 15 of the frame and constitute extensions of the members 40 and 41 respectively. These extension pieces when folded enclose the side of the frame as in Fig. 7. To retain the members 60 and 61 in open position, I have 20 shown a pair of hinged end members 62 and 63 which extend transversely of the frame and which when open constitute extensions of the end members 42 and 43, respectively, of the frame. These end extension sections are preferably hinged to the side extension sections and may be operatively connected by rings 64 and 65 respectively. In extended position, the end extension sections rest upon the edges of the 25 end members of the frame as shown in Fig. 5, and thus prevent the chair from collapsing.

When the chair is in open position, it may be supported upon the lowermost edges of 30 the extension portions. To adjust the height however, I may employ extensible legs or standards 70 and 71 which are hinged to the sides of the frame and are adapted to be folded within the frame whence the chair 35 is closed. These legs are shown as hinged at 72 and 73 respectively on pivots spaced inwardly from the ends 42 and 43 respectively, wherefore the normal inclination of the legs tends to prevent collapsing when the 40 chair is in use.

From the foregoing description, it will be seen that my invention provides a play chair which is well adapted for use in single or multiple units and when so constructed provides a chair having a removable and flexible seat. Moreover, a chair made according to my invention is light and yet sufficiently strong for the required purpose and is capable of being cheaply manufactured.

55 I claim:—

1. A foldable chair comprising a collapsible frame having an opening in one side thereof, a seat disposed within the frame

beneath the opening, and a closure for the opening, said closure being adapted to open 60 outwardly to provide a table when in open position, said closure and frame cooperating to form an enclosed article when the chair is collapsed.

2. A foldable chair comprising a frame 65 having an opening in one side thereof, a closure for said opening, a seat removably attached to the frame adjacent the opening, hinged members on the frame adjacent the opening, one of said members comprising a 70 table, and the other of said members comprising a back rest, and extension members carried by the frame on the side opposite the opening, said members and closure cooperating with the frame to provide an enclosed case when the chair is in folded position.

3. A foldable chair comprising in combination a frame having an opening in one side thereof, a flexible seat disposed within the 80 frame adjacent the opening, members hinged to the frame on opposite sides of the opening and comprising a table, and a back rest respectively, and a lever pivotally connected to one of said members, said lever having 85 a lost motion connected with the other of said members, whereby operation of one controls movement of the other member.

4. A foldable chair comprising a frame having an opening in one side thereof, a seat 90 carried by the frame and disposed within the opening, a closure for said opening, standards pivoted to the frame beneath the closure and extension members associated with the frame on the side opposite the 95 opening, said members and closure cooperating with the frame to provide an enclosed casing when the chair is in folded position and said members cooperating with the standards to maintain them in extended position when the chair is open.

5. A foldable chair comprising in combination, a frame having an opening therein, a flexible seat disposed within the frame and across the opening, a closure for the opening, 105 an extensible section carried by the frame, and standards carried by the frame and adapted to be positioned therein when the chair is folded, the standards when in extended position being in engagement with the extensible sections whereby the weight of the occupant tends to hold the chair in open position.

In testimony whereof, I hereunto affix my signature.

ROBERT C. MACKLEM.
